UNITED STATES PATENT OFFICE.

LEANDER J. McCORMICK, OF CHICAGO, ILLINOIS.

IMPROVEMENT IN GRAIN-BINDERS.

Specification forming part of Letters Patent No. **222,416**, dated December 9, 1879; application filed December 12, 1876.

To all whom it may concern:

Be it known that I, LEANDER J. McCORMICK, of Chicago, in the county of Cook and State of Illinois, have invented certain new and useful Improvements in Automatic Grain-Binding Mechanism, of which the following is a specification.

The first part of my invention more especially relates to that class of automatic grain-binders in which the binding mechanism is mounted upon a traversing carriage, as in the well-known Withington binder built by C. H. & L. J. McCormick at Chicago, Illinois.

In this machine the binding mechanism is adjustable to suit the varying length of grain, so as always to bind the gavel in the middle by mechanism operated by the driver from his seat, as shown, for instance, in Letters Patent No. 174,454, granted to said Withington March 7, 1876.

The objects of this part of my invention are to simplify the construction of this adjusting mechanism, and to adjust the binding mechanism automatically at the will of the driver by the same power which actuates the other mechanism.

These ends I attain by combining the adjustable frame which the reciprocating binding-carriage traverses with the driving-gearing rotating continuously in one direction when working, by means of a link-rod, a crank, a spur-pinion, and a worm-wheel interposed between the binding-carriage and driving-gearing, as hereinafter more fully set forth.

The next part of my invention relates to the wire-supplying mechanism of the binder. Its objects are, while securing a free delivery of the binding-wire, to maintain a uniform pressure upon it, notwithstanding variations in the size of the spool upon which it is wound, and also to prevent the wire flying from the spool in case the wire should break. These ends I attain by combining a wire-spool having projecting axles or trunnions with slotted supporting arms or brackets, in which slots the trunnions traverse and turn, a skeleton frame secured upon said arms beneath the trunnions of the spool, and a flexible band stretched across said frame, upon which band the periphery of the wire coil rests, as hereinafter more fully set forth.

The next part of my invention relates to the mechanism for compressing the gavel before it is bound, and, more especially, to that class of compressors exerting spring-pressure upon the gavel.

The object of this branch of my improvement is to allow great freedom of movement to the spring-arm of the compressor, so as to prevent its binding or straining, which ends I attain by combining a binding or wire-carrying arm vibrating on a suitable pivot or support intermediate of its length, a compressing-arm also vibrating or swinging on a suitable support, a slotted ribbed head mounted on the heel-extension of the binder-arm, a connecting rod or link pivoted on the compressor and passing through the slotted head, and a spiral spring encircling the connecting-rod between the compressor-arm and the slotted head, as hereinafter more fully set forth.

The accompanying drawings represent all my improvements as embodied in one machine in the best way now known to me. Obviously, however, some of them may be used without the others, and in machines differing somewhat in the details of their construction from those herein shown.

Figure 1 represents a plan or top view of so much of a binding-machine embracing my improvement as is necessary to illustrate the subject-matter herein claimed, with the binder-arm and compressor elevated. Fig. 2 represents a side elevation of the same, and Fig. 3 a front view thereof. Fig. 4 represents an inverted plan view, partly in section, on the line 1 1 of Fig. 3, of the binding-frame adjusting mechanism. Fig. 5 represents a vertical section through the wire-spool and its tension on the line 2 2 of Fig. 1. Fig. 6 represents a front view of the binding-arm and compressor in the act of closing. Fig. 7 represents a vertical longitudinal section, on the line 3 3 of Fig. 8, through the slotted head in which the connecting or compressor rod slides. Fig. 8 represents a top view of the same head, and Fig. 9 represents a transverse vertical section through the machine on the line 4 4 of Fig. 1, showing some of the details of the sliding carriage.

The mechanism is shown as mounted upon a stout frame, Δ , capable of attachment to the

ordinary harvester-frame in the usual well-known ways.

An adjustable frame, B C, rests upon this frame and is movable thereon, being held down by suitable hooks $b' b'$, embracing the stationary frame A, and prevented from lateral displacement by a guide-rail, b^2 , Figs. 1, 2, and 9.

I prefer to make the portion C of the adjustable frame, at least, of metal, and provide it with ways $c' c'$, upon which the reciprocating binder-carriage D slides. A long shaft, E, turning in fixed bearings in the stationary frame A, turns loosely in journals or pipe-box bearings $e' e'$ upon the sliding frame, which is capable of moving freely endwise upon the shaft. A sprocket or other suitable driving wheel, F, driven in any of the usual well-known ways from the harvester itself, carries a spur-wheel, F', which gears into a corresponding pinion, g, capable of sliding freely upon a shaft, h, and controlled by a shifting-lever, G, of usual well-known construction. A worm, H, mounted upon the shaft h, gears into a spur-pinion, I, turning on a shaft, i, mounted on a suitable bracket secured to the frame. A crank-arm, I', on this pinion is pin-jointed to one end of a link-rod or pitman, J, the other end of which is connected with a stud, c^2 , depending from the adjustable frame C.

By this mode of construction, when this mechanism is thrown into gear, the crank-arm I' rotates and moves the frame C backward or forward, carrying the binding-carriage with it, thus adjusting the wire to the middle of the grain lying upon the platform, and adapting the binding mechanism to different lengths of grain; but the adjustment, it will be observed, is made in either direction by the continuous rotation of the driving-shaft in one direction, the direction or length of adjustment being dependent upon the length of time the gear continues to operate.

When thrown out of gear the machine, of course, rests in the position where it is left at the moment of disengagement.

The advantages of this arrangement are obvious, as the adjustment is automatically effected by the gearing, which can readily be stopped or started by the hand or foot of the driver without compelling him to exert his strength to adjust the binding mechanism.

The shaft E is secured to the frame A by means of a yoke-plate, which embraces a collar on the shaft, and thus prevents it from moving endwise, while leaving it free to turn. The removal of this plate permits the shaft to be withdrawn, so that the binding-frame can readily be removed from its supporting-frame. (See Fig. 4.)

A wire-spool, K, is provided with projecting axles or trunnions k, capable of turning freely and moving up and down in vertical slots in bracket-arms or supports k', mounted upon the binder-carriage. A skeleton frame, L, is secured upon and encompasses the bracket-arms below the spool-axes. (See Figs. 1, 2, and 3.)

A belt or strip of leather, rubber, or other suit-

able flexible or yielding material is stretched across the frame L in such manner that the periphery of the wire-coil itself always rests upon this band, the reel descending in its slots for this purpose as the coil of wire diminishes in diameter. The pressure of the wire and its spool upon the belt causes it to sag somewhat and conform to an increased portion of the circumference of the wire-coil, thus creating additional friction. A constant friction is thus exerted upon the wire to prevent its paying out too rapidly, and the flying or uncoiling of the wire, in case of breakage, is also prevented.

A vibrating binding-arm, M, is mounted upon a rock-shaft, M', turning in bearings in the binding-frame, substantially as in the Withington patent above mentioned, and as shown and described in Letters Patent of the United States of Wm. R. Baker, dated May 22, 1877, No. 190,096. A heel or arm, m, projecting beyond the back of the axis of oscillation of the binding-arm, carries a sliding head, n, slotted vertically and provided with inwardly-projecting ribs or pins, as shown in Figs. 7 and 8.

A compressor-arm, O, swings around its pivot o on a projecting portion of the binder-carriage.

A spring-arm or link-rod, N, pin-jointed at one end to the compressor at a point intermediate of its length, passes through the slotted head n above mentioned. This rod is encircled by a coiled spring tending to press it outward in the position shown in Fig. 3. When the compressor and binding-arm are retracted the spring is uncompressed; but when the arm M descends to compress the gavel it compresses the spring, as shown in Fig. 6, and causes the compressor to squeeze the gavel tightly, but with an elastic pressure, while being bound. With the exception of the slotted head, the above-described mechanism for compressing the gavel is substantially the same as that shown and described in the before-mentioned patent of Wm. R. Baker, and is not claimed by me.

By the above-described construction of the slotted head, the spring-rod N is allowed free angular play or rocking motion therein, as well as endwise movement therethrough, without the necessity of pivoting the head, or causing it to swivel, as in the said Baker's patent.

It is deemed unnecessary to describe in detail the other parts of the mechanism, as they form no part of the subject-matter herein claimed, and are, for the greater part, fully shown in Baker's and Withington's patents, before mentioned.

I do not broadly claim binding mechanism adjustable backward or forward by gearing adapted to be thrown into or out of connection with a constantly-moving portion of the gearing of the machine; nor, broadly, the combination of a traction-wheel, shifting binding mechanism, and intermediate mechanism

adapted to effect the adjustment of the binding mechanism by the traction of the wheel; nor, broadly, the combination of adjustable binding mechanism, driving-gearing, and intermediate connecting mechanism whereby the binding mechanism may be adjusted in either direction by gearing rotating in one direction; but limit my claim to the specific organization of the above-mentioned devices, hereinbefore set forth.

Neither do I claim a traveling binding-carriage carrying a binder-arm upon an overhanging bracket, and gathering and binding the grain as it reciprocates.

Neither do I broadly claim a grain-receiving platform having ways combined with a binding-carriage traveling back and forth on said ways to gather and bind the grain.

I claim as my invention—

1. The combination, substantially as hereinbefore set forth, of the reciprocating binding-carriage, the adjustable frame which it traverses, the pitman or link-rod pivoted to the adjustable frame, the crank pivoted to the link-rod, the spur-pinion by which the crank is driven, the worm-wheel driving the pinion, and the gearing driving the worm-wheel.

2. The combination of the bracket-arms, the self-adjusting wire-spool with projecting axles resting in slots in the bracket-arms, the skeleton frame secured upon said arms beneath the axles of the spool, and the flexible band stretched across said frame and supporting the weight of the wire coil, these members being constructed and operating as hereinbefore set forth.

3. The combination of the slotted ribbed head *n*, the spring-rod moving endwise therethrough and having a sidewise or rocking motion independently thereof, the vibrating binding-arm, to the heel-extension of which said slotted head is secured, and the swinging compressor-arm, to which the spring-rod is pivoted, these members being constructed and operating as set forth.

In testimony whereof I have hereunto subscribed my name.

LEANDER J. McCORMICK.
